McHayes

ATTORNEY

UNITED STATES PATENT OFFICE

2,567,206

CARRIER

Vincent J. Hepp, Philadelphia, Pa.

Application March 21, 1947, Serial No. 736,187

3 Claims. (Cl. 294—67)

(Granted under the act of March 3, 1883, as
amended April 30, 1928; 370 O. G. 757)

1

This invention relates to improvements in carriers and more particularly to improvements in devices for gripping and transporting an object.

The primary object is to provide a carrier of simple and durable construction adapted to grip an object and serve as a holder for transporting said object.

Another object is to provide a carrier adapted to grip an object disposed in a horizontal or angular position and serve as a holder for transporting said object in a vertical position.

Another object is to provide a carrier adapted to grip an object and serve as a holder for transporting said object in such a manner that a delicate or sensitive portion of said object will not be disturbed.

Further objects and advantages of this invention, as well as its construction, arrangement and operation will be apparent from the following description and claims in connection with the accompanying drawing, in which

Fig. 1 is a plan view of a carrier, showing a preferred embodiment of the invention; and

Fig. 2 is a side view thereof.

Similar numerals refer to similar parts throughout the several views.

A first arcuate band 11 is hinged to a second arcuate band 13 by a hinge 15 provided with a hinge pin 17 to form a collar that describes more than half of the circle defined by said bands. A spring arm 19 secured to the periphery of said first band 11 adjacent said hinge by bolts 21 extends over the periphery of the adjacent portion of said second band 13 to retain said second band from pivoting outwardly relative to said first band on the axis of said hinge pin.

Lugs 23 and 25 positioned at spaced points on the peripheries of the bands 11 and 13 respectively, preferably at the points of intersection of a diameter of the defined circle and said bands, are provided with bores 27 and 29 respectively, said bores being adapted to receive a chain hereinafter described.

Legs 31 and 33 secured to and dependent from spaced points on the peripheries of the bands 11 and 13 respectively, preferably intermediate said hinge and said lugs respectively, are provided with feet 35 and 37 respectively, said feet being disposed inwardly distal said bands, and preferably parallel to radii of the circle defined by said bands when said bands are in normal or contracted position.

An endless chain 39 of suitable length passes from a gripping ring 41, through the lug 23,

2

thence around the periphery of said bands through the lug 25 and thence back to the said ring 41.

When the bands 11 and 13 are distended and then released in such juxtaposition to the object that the said bands encircle a portion of the body of an object, the legs 31 and 33 lie adjacent to said object and the feet 35 and 37 are disposed contiguous to an end of said object. The spring arm 19 retains said bands in engagement with the object, and by engaging the gripping ring 41 and pulling said ring away from the object, the chain 39 is made suitably taut and the object can be transported. After the object has been moved to a desired location, the carrier is disengaged therefrom by distending said bands.

It is apparent that the carrier is adapted to grip and transport an object of any shape and is particularly suited to grip and transport cylindrical objects. It is further apparent that the carrier can be employed to grip one or more of a plurality of objects stowed horizontally and transport said object or objects in a vertical position.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A carrier comprising a first arcuate band, a second arcuate band hinged to said first band and rotatable in relation thereto, the peripheries of said bands in one position defining the greater portion of a circle, a spring secured to the periphery of said first band extending over the periphery of said second band and adapted to restrict rotation of said second band with relation to said first band, a plurality of legs in spaced relation dependent from said bands, said legs having a portion distal said bands extending inward to form a base for an object, a plurality of lugs in spaced relation secured to said bands and means engaging said lugs for lifting said carrier.

2. A carrier comprising a first arcuate band, a second arcuate band hinged to said first band, the peripheries of said bands in one position defining the greater portion of a circle, a spring secured to the convex face of said first band extending over a portion of the convex face of said second band and adapted to restrict rotation of said second band with relation to said first band, a plurality of legs in spaced relation dependent from said

bands, said legs having a portion distal said bands extending inward to form a base for an object, a lug having a bore therethrough secured to each of said bands, and an endless chain passing through said bores.

3. A carrier comprising a first arcuate band, a second arcuate band hinged to said first band, the peripheries of said bands in one position defining the greater portion of a circle, a spring secured to the convex face of said first band extending over a portion of the convex face of said second band and adapted to restrict rotation of said second band with relation to said first band, a plurality of legs in spaced relation dependent from said bands, said legs having a portion distal said bands extending inward to form a base for an object, a lug having a bore therethrough secured to each of said bands medial the convex face of each said band, and an endless chain passing through said bores.

VINCENT J. HEPP.
